UNITED STATES PATENT OFFICE.

JOHN STRATTON AND ERNEST ALEXANDER CLAREMONT, OF COUNTY OF CHESTER,
ENGLAND.

GLAZING-BAR.

1,171,073.

Specification of Letters Patent.

Patented Feb. 8, 1916.

Application filed May 19, 1915. Serial No. 29,092.

To all whom it may concern:

Be it known that we, JOHN STRATTON and ERNEST ALEXANDER CLAREMONT, subjects of the King of England, residing in Chester county, England, have invented certain new and useful Improvements Relating to Glazing-Bars, of which the following is a specification.

Our invention has reference to roof glazing in which the glass is held by lead coated steel or other metal glazing bars.

Hitherto it has been the practice to fix the glazing bars to the purlins by means of screws passing through holes drilled through the bases of the glazing bars and in some cases to hold the latter at their lower extremities in clips fastened to the purlins by screws passing through holes in the bases of the clips.

With such methods of fastening as above described moisture may enter at the holes through which the screws pass and reach the steel or other metal core of the bars or clips causing rust and deterioration and ultimate destruction.

According to the present invention we construct a lead coated glazing bar without any holes and without any joints or cracks or crevices in the lead coating through which moisture can creep and we fix and hold the glazing bar in position at each end by means of clips or shoes.

In the accompanying drawings an embodiment of our invention is illustrated.

In all the figures the same letters refer to similar parts.

Figures 1, 2 and 3 are respectively a side elevation, an end elevation viewed from the inner side, and a plan of the clip or shoe used at the lower end of the glazing bar. Figs. 4, 5 and 6 are respectively a side elevation, an end elevation viewed from the outer side, and a plan of a bolt hereinafter described. Figs. 7 and 8 are respectively an end elevation viewed from the inner side, and a plan of the shoe used at the upper end of the glazing bar. Figs. 9 and 10 are respectively a side elevation, and sectional elevation of said upper clip or shoe, the section of Fig. 10 being taken on the line X—Y of Fig. 7. Figs. 11 and 12 are respectively a partial side elevation and a plan showing the general arrangement of a glazing bar with the shoes fixed in position, the upper

section of the bar being partially cut-away in Fig. 12 to show the position of the base of the bar in relation to the upper clip.

The clip or shoe at the upper end of the bar consists of a flat strip of metal having a base or main part C with one end bent up 60 rectangularly as at C¹ or at other suitable angle. When in position the end of the glazing bar A rests on the base or main part of the clip or shoe with its extremity abutting against the bent end as shown in Figs. 11 and 12, said bent end extending upward beyond the vertical web A¹ of the glazing bar. On the bent end of the clip or shoe there is formed a curved hood-like projection F adapted to fit over said vertical web A¹ of 70 the bar and hold it in position. The base C of the clip or shoe is beveled on the under side laterally as at C² to enable the shoe to be slightly tilted and hence the hood to be raised to some extent when the bar is inserted into it end on, the hood being then brought into its correct position embracing the web of the bar, and the shoe screwed down firmly to its support. Obviously, if the shoe were rigidly fixed in its final position in the first instance, more clearance would have to be provided below the hood to enable the bar to be pushed into position. The clip or shoe located at the lower end of the bar is made and fitted substantially to 80 the upper cap or shoe similarly and consists of the base B with rectangularly bent end B¹ but no hooded projection F is provided. In lieu thereof there is provided a bolt (see more particularly Figs. 4 to 6) formed with 90 a threaded shaft to pass through a hole B³ in the bent end B¹ and provided with a nut E² and a washer E¹ whereby said bolt can be attached to the bent end B¹. The said bolt has a U shaped head E which fits over the 95 vertical web A¹ of the bar and thus holds it in position. Alternately the U shaped head E may be held by passing a screw from the outer side of the bent end B¹ of the clip or shoe into a threaded socket in said head as 100 will be readily understood.

Through the base B, C respectively of each of the clips or shoes are formed two or more holes G to receive screws G¹ to fasten them to the purlins H. The clips or shoes 105 are formed of a core of steel or other suitable metal coated with lead throughout including the inner part of the holes G, as

more particularly shown in Fig. 10 where I designates the core and J the lead coating. The holes G are of such size that when the screws G¹ are passed through them there is a clearance between the screw and the sides of the hole. The heads of the screws are supported on washers G².

The bolt E above referred to and all screws and washers are made of copper or other non-corrosive metal.

The bases or main parts of the shoes, for example the upper shoe, can be cut away down the center as at C³ in which case it resembles two parallel strips or tongues as shown in Fig. 8 and the bent end can be cut away at the corners so that the end is rounded or semi-circular in shape as shown in Figs. 2 and 7. Further the base or main part is preferably widened as shown in order that the screw holes G may be positioned at a substantial distance from the bar and to render the attachment of the clip more secure.

It is practicable to make the base or main part C of the upper shoe considerably shorter than that B of the lower shoe, since it has to take less strain and need not be so firmly attached to the purlin and further it may be desirable to provide the base or main part of said lower shoe with lateral up bent flanges D to prevent the bar from moving laterally.

With a glazing bar constructed and fixed as above described the whole of the steel or other corrosive metal of which the core is formed is completely coated with lead without any crevices or cracks or holes through which water can reach it and in the drawings the outlines of the steel or other metal core or foundation and of the lead coating respectively are shown by broken and continuous lines respectively.

In the application of our invention we proceed as follows:—The lower and upper shoes are first fixed to the purlins as shown in Fig. 11, the screws G¹ of the upper shoe being left loose to permit of it being tilted on its beveled base C² slightly to enable the bar to be passed under the hood F. After the bar is placed in position the bolt E is passed through the hole B³ provided in the bent end B¹ of the lower shoe and secured in position with the washer E¹ and nut E².

What we claim as our invention and de-

sire to secure by Letters Patent of the United States is:—

1. The combination with a lead coated glazing bar of lead coated clips or shoes adapted to support the upper and lower ends of said bar, each of said clips comprising a base or main member on which said bar rests, and an angularly disposed member against which an end of the bar abuts, a detachable bolt on one of said clips having a hood shaped end, and an integral hood shaped member on the other of said clips, the bolt and hood shaped member being adapted to embrace the upper part of the glazing bar.

2. A clip or shoe for use with glazing bars comprising a base member, an end member disposed angularly thereto and a bolt having a hood shaped end in detachable relation to said end member.

3. A clip or shoe for use with glazing bars comprising a base member, an end member disposed in angular relation thereto, a bolt in detachable relation to said end member and having a hood shaped end extending over said base member, and upwardly extending lateral flanges on said base member.

4. The combination with a lead-coated glazing bar, of a clip or chute adapted to support an end of said bar, said clip or chute consisting of a base or main member comprising two wings between which said bar rests, the lower face of one of said wings being beveled laterally, an angularly disposed member against which the end of the bar abuts, and means on said angularly disposed member for embracing the upper part of the bar.

5. A clip or chute for use with glazing bars comprising a base member interrupted to provide two wings between which the bar is received, the lower surface of one of said wings being beveled laterally, an end member disposed in angular relation to said base member, and a hood formed integral with said end member and disposed angularly thereto.

In witness whereof we have signed this specification in the presence of two witnesses.

JOHN STRATTON.

ERNEST ALEXANDER CLAREMONT.
